UNITED STATES PATENT OFFICE.

SANDER DEBUS, OF HASTINGS, NEBRASKA.

SHIPPING BOX.

Application filed June 17, 1925. Serial No. 37,779.

This invention relates to an improved returnable shipping box particularly designed for use in shipping bread, and seeks, among other objects, to provide a box which will 5 effectually withstand the wear and tear and rough handling which such a box must necessarily encounter.

The invention seeks, as a further object, to provide a box wherein the side and end 10 walls of the box body will be rigidly braced and secured together.

Another object is to provide a box embodying novel corner braces for connecting the side and end walls of the box with each 15 other.

Still another object is to provide a box wherein the upper corner braces employed will serve to protect the lid as well as retain the lid in centered relation upon the box 20 body when the lid is closed.

And the invention seeks, as a still further object, to provide a box wherein a pair of the upper corner braces will further serve to 25 swingingly support the lid.

Other and incidental objects will appear hereinafter.

In the accompanying drawings:

Figure 1 is a perspective view of my improved shipping box.

Figure 2 is a vertical sectional view on the line 2-2 of Figure 1, looking in the direction indicated by the arrows.

Figure 3 is a fragmentary horizontal sectional view on the line 3-3 of Figure 1, 30 looking in the direction indicated by the arrows, this view particularly showing the manner in which the side and end walls of the box body are connected by the corner braces.

Figure 4 is a fragmentary horizontal sectional view on the line 4-4 of Figure 1, looking in the direction indicated by the arrows.

Figure 5 is a perspective view showing a 40 pair of upper and lower corner braces.

Figure 6 is a fragmentary perspective view showing the hinged mounting of the lid.

In carrying the invention into effect, I 50 employ a rectangular metal box body having a bottom wall 10, and end walls 11. As particularly shown in Figures 3 and 4, the side and end walls are bent at their vertical margins to form pairs of vertically extending abutting flanges 12 which project obliquely at the corners of the box body ex-

ternally thereof. These flanges extend the full height of the box body.

Connecting the side and end walls of the

box body with each other are lower corner 60 braces 13 and upper corner braces 14, a pair

of which is shown in Figure 5. These corner braces are stamped from suitable sheet

metal and considering first the lower corner 65 braces, it will be seen that said braces are

each formed with angularly disposed wings

15 which are reinforced at their margins by

longitudinally extending beads 16. At their

lower ends, said wings are bent to provide

rectangular bottom channels 17 and are fur-

ther bent longitudinally to provide vertical

U-shaped corner channels 18 which extend

from the upper sides of the channels 17 to

the upper ends of the wings and project

obliquely at the angle between the wings. 75

The channels 18 snugly accommodate the

pairs of flanges 12 of the side and end walls

11 of the box body while the wings 15 over-

lie said walls adjacent the corners of the

body, and extending transversely through

the channels and through said pairs of

flanges are spaced rivets 19 rigidly securing

the parts together. Fitting at their ends

within the channels 17 of said braces, as

particularly seen in Figure 2, are the side 85

and end bottom rails 20 of a reinforcing

frame lying beneath the bottom wall 10 of

the box body, and extending between said

end rails is a center rail 20'. Also fitting at

their ends in said channels are lower rein-

forcing rails 21 resting upon the project-

ing margins of the bottom wall in the an-

gles between said margins and the side and

end walls. The rails 20 and 21 are fixed in

the channels by suitable fastening devices

extending through the outer vertical walls

of said channels and not only serve to rein-

force the side, end and bottom walls of the

box body but, as also shown in Figure 2,

house the angles between the side and end

walls and the bottom wall of the box body

for protecting said angles against injury.

All of said rails are preferably of wood.

The upper corner braces 14 are quite simi-

lar to the lower corner braces and are formed

with angularly disposed wings 22 reinforced

by beads 23. Near their upper ends, the

wings are provided with offsets 24 from

which rise flanges 25 while below said off-

sets, the wings are bent longitudinally to

provide vertical U-shaped corner channels

26 which extend from said offsets to the

lower ends of the wings and project obliquely at the angle between the wings. The channels 26 of the upper corner braces, like the channels 18 of the lower corner braces, 5 snugly accommodate the pairs of flanges 12 of the side and end walls of the box body, and extending through said channels and through said pairs of flanges are vertically spaced rivets 27 rigidly securing the parts 13 together.

As shown in Figure 2, the adjacent ends of the upper and lower corner braces meet medially of the box body and overlying said ends of the braces are channel-shaped angle 15 braces 28. Fitting at their ends in said angle braces are intermediate reinforcing rails 29 riveted or otherwise secured to said braces. Fitting at their ends within the angles of the flanges 25 of the upper corner braces 14 20 are upper reinforcing rails 30 resting on the offsets 24 of said braces and snugly received between said flanges and the side and end walls of the box body flush with the upper edges of said walls. The rails 30 are riveted or otherwise secured to said flanges and will protect and reinforce the box body 25 at its upper end while the rails 29 will protect and reinforce the box body medially thereof. The rails 29 and 30 are preferably 30 of wood, and formed in the side and end walls of the box body immediately below said rails are rows of ventilating openings 31 while, as shown in Figure 3, the bottom wall 10 is also provided with rows of similar 35 openings 32. Secured to those of the rails 29 which lie at the ends of the box body are suitable handles 33.

Normally closing the box body is a lid 40 comprising a frame having side and end rails 34, and extending between the end rails are longitudinal brace rails 35. These rails are preferably of wood, and secured to the frame at its upper side is a preferably sheet

metal cover 36. As shown in Figure 2, the lid is adapted to snugly fit within the flanges 45 25 of the upper corner braces 14, resting upon the box body in closed position so that said flanges will, when the lid is closed, thus retain the lid in registering relation to the box body, and fixed to the lower side of the 50 rear side rail of the frame of the lid, near the ends of said rail, are hinge plates 37. As shown in detail in Figure 6, the plates 37 are provided with upwardly curved rear ends 38, and formed in the adjacent flanges 55 of the rear upper corner braces 14 are slots 39 freely receiving the curved ends of said plates. Thus, the lid is swingingly connected with said flanges so that the lid may be readily opened or closed and, as will be 60 observed, said flanges of the corner braces are widened somewhat to accommodate said slots.

Having thus described the invention, what I claim is:

A box body having abutting flanges projected outwardly from its walls at the corners, top, bottom and intermediate rails at the outer side thereof, angle braces connecting the intermediate rails, upper and lower 70 corner braces comprising wings and connecting channels, the latter snugly embracing the said abutting flanges, the wings of the lower braces being widened and formed with offset channels engaging the bottom 75 rails, and the wings of the upper braces being widened and formed with offset flanges engaging the top rails and extended above the same, a lid resting upon the top rails within the extensions of the flanges of 80 the upper corner braces, and hinge elements connecting the lid with the flanges of the upper rear corner braces.

In testimony whereof I affix my signature.

SANDER DEBUS. [L.S.]
